BOWLING PIN SETTING MACHINE

Willis L. Wells, St. Louis, Mo., assignor to American Machine & Foundry Company, a corporation of New Jersey

Original application Mar. 24, 1948, Ser. No. 16,725, now Patent No. 2,707,636, dated May 3, 1955. Divided 10 and this application July 7, 1954, Ser. No. 441,799

19 Claims. (Cl. 273—43)

This invention relates to blowing pin spotting machines and more particularly in improvements in machines for automatically spotting and respotting pins on the playing bed of a bowling alley, and interconnected and cooperating mechanisms for controlling the operation of the machine to effect the necessary handling of pins incident to their removal from the pit of a bowling alley and replacement in playing arrangement on the playing bed.

Problems encountered in the design and construction of the bowling pin spotting machines are those of reducing weight, simplifying their design, and providing mechanism which will handle bowling pins efficiently and with a minimum of wear and tear.

This application constitutes a division of application S.N. 16,725, filed March 24, 1948, for Bowling Pin Setting Machine, and now Patent No. 2,707,636.

The present invention relates to a machine which is lighter in weight, relatively simple in design, and easy to control. The pins handled are subjected to less wear and tear on removal from the pit of the alley and on being delivered to the necessary pin spotting mechanism. The ball, also, is handled by improved mechanism which tends to substantially reduce or eliminate chipping and unnecessary wear in its removal from the pit and delivery to the player.

The invention solves the problem of distributing pins in a simple and expeditious manner into triangular arrangement for delivery by the spotter onto the playing alley. This is accomplished by providing a substantially vertically positioned pin magazine having triangularly arranged pin supporting stations corresponding with the positions normally occupied by standing pins on the alley. A conveyor, which receives the pins in the pit of the alley, is responsible for the delivery of the pins into the several stations in the magazine where they are positioned in substantially horizontal arrangement, one above the other, with their handle ends projecting outwardly from the magazine. A pin spotter provided with triangularly arranged gripping members is moved into position adjacent the magazine. The members grip the handle ends of the pins in the magazine after which, the spotter moves away from the magazine and in so doing, a full set of pins is moved thereby horizontally out of the magazine and delivered in proper playing position onto the playing bed of the alley.

The invention also solves the problem of storing one or more sets of pins and holding them in reserve while one or more sets of pins is being used or engaged in active play. According to the invention, whenever desired, pins in reserve can be removed from storage and quickly substituted for active pins which are placed in storage.

It is an object of the invention to provide an improved bowling pin spotting machine which is relatively simple in construction and capable of handling pins with a minimum of wear and tear, thereby increasing the life of each

2

pin handled by the several pin engaging parts of the machine.

The invention also consists in the provision of improved pin triangularizing mechanism which includes a vertically arranged magazine into which pins are delivered in substantially triangular formation corresponding to the positions the several pins will assume when transferred by the pin spotter from the magazine and placed on the playing bed of the alley.

With these and other objects not specifically mentioned in view, the invention consists in certain combinations and constructions which will be hereinafter fully described, and then set forth in the claims hereunto appended.

In the accompanying drawings, which illustrate preferred embodiments on the invention and form a part of the specification, and in which like characters of reference indicate the same or like parts:

Figure 1 is a sectional front elevation—taken on line 1—1 of Figure 2—illustrating a preferred form of triangularizing pin magazine, and pin and ball elevating mechanisms;

Figure 2 is a sectional side elevation—taken on line 2—2 of Figure 1—illustrating the pin magazine in conjunction with a pin spotting table, and means for sweeping the pins from an alley bed into a pit from which the pins are conveyed into the pin magazine;

Figure 3 is a partial sectional front elevation of the pin magazine showing a modified form of construction of the triangularizing section of the pin magazine;

Figure 4 is a section plan view—taken on line 4—4 of Figure 1—illustrating the ball elevator, and a portion of the pin conveyor of the magazine;

Figures 5 and 6 are front elevations of two modified pin stations of the triangularizing rack of the pin magazine;

Figure 7 is a sectional side elevation of the ball elevating and return mechanism;

Figure 8 is a perspective view showing a portion of the modified form of construction of the triangularizing section of the pin magazine illustrated in Figure 3;

Figure 9 is a partial front elevation of the preferred form of the triangularizing rack section of the magazine illustrating the delivery of the pins to various pin stations.

Figures 10 to 17 are schematic front views of the pin magazine illustrating the successive step in the sequence of operations involved in automatically transferring two sets of pins in storage from the storage bin to the triangularizing or rack section of the magazine and to the alley bed, and depositing two sets of pins in use from the rack section of the machine and alley bed into the storage bin.

Figure 18 is a wiring diagram illustrating a suitable electrical control mechanism necessary to effect a normal operation of the machine, as well as a changing of pins in the same.

Figure 19 is a view of a modified control which can be used with the circuit shown in Figure 18 to change single sets of pins.

The bowling pin setting machine selected for purposes of illustration, consists chiefly of a magazine M, a pin setting table T, an alley sweep S and a pit sweep PS. Within the magazine M, are arranged a pin conveyor CO, a triangularizing or rack section R, a ball lift L, a ball elevator E, and a pin storage bin SB.

The magazine M consists of an upright rectangular housing or frame 25 which at its four corners carries a number of suitably mounted studs 26 on each of which are loosely mounted pairs of spaced sprockets 28 on which run two spaced endless chains 30 which form part of the pin conveyor CO. Chains 30 are connected by

means of equally spaced bars 32 and are driven by a pair of sprockets 34 mounted on a shaft 36 supported by suitable bearings attached to magazine housing 25. Shaft 36 is driven by means of a suitable pulley (not shown) attached thereto through a belt 38 from a pin conveyor drive motor 40. A number of pivotally mounted cradles or flight 42 are equidistantly spaced along chains 30 (Fig. 1), and each flight is provided with a pair of guide shoes 44 employed for positioning the several flight properly when passing through the various sections of the magazine M, as described hereinafter. Flights 42 convey pins from lower chamber F (Figures 1 and 2) of magazine M, into which the pins are delivered by pit sweep PS, to the triangularizing or rack section R. While passing through the lower chamber F, flight 42 together with chains 30 and bars 32, from a more or less horizontal moving band conveyor or moving floor onto which the pins are deposited by pit sweep PS. As the chains turn the right lower corner of magazine M, and move vertically upward (Fig. 1), each flight on which a pin is resting carries it upward, the latter resting in a horizontal position thereon.

Since it is necessary that all pins delivered into the triangularizing or rack section R protrude with their heads in a forward direction toward the pin supporting bed of the alley, all pins conveyed by flights 42 must also lie with their heads or handle ends forward. If a pin comes to rest on a flight 42 in a butt end forward direction, such pin must be oriented or have its position changed to a head forward direction before reaching the triangular rack section R. The necessary change in position or orienting of pins can be effected by causing pin conveyor CO to move through a horizontal, substantially U-shaped loop channel U (Fig. 1). While passing through the lower portion of channel U, flights 42 assume a vertical position, such that a pin engaged by a flight is rolled or pushed in a barrel-like fashion substantially horizontally over the bottom position designated generally 50. Bottom portion 50 is provided with a pair of suitable spaced guide rails 52 employed for the purpose of facilitating the rolling of the pins and assuring their horizontal movement. The bottom portion 50 of the channel is so designed as to provide a narrow bridge plate 54 (Figures 1 and 2) which bridges the rear portion of a chute 56. The latter is equipped with a pair of spaced suitably curved pin reversing plates 58 and, on its bottom portion, provided with an opening 60 leading to the ascending section pin conveyor CO. All pins which are lifted from the lower chamber F by flights 42, and are conveyed upwardly thereby in a head forward position, are easily and safely rolled or pushed over the narrow bridge plate 54 as illustrated in broken lines by pin 100 in Figure 2. If, however, a pin is moved into channel U in a butt-end forward position, it will, upon reaching bridge plate 54, because of the position of the center of gravity thereof, tumble over the edge of plate 54 and slide down chute 56, as illustrated in broken lines by pin 200 in Figure 2. The butt end of such falling pin will strike pin orienting or reversing plates 58 with the effect of being guided into a head forward position, as illustrated by pin 300 in Figure 2. This properly oriented pin then falls through opening 60 of chute 56 onto one of the ascending flights 42. In case one of the ascending flights already carries a pin, then the just oriented pin is simply pushed aside by the ascending pin and cannot fall onto a flight until an empty flight passes opening 60. After successfully passing the lower portion 50 of the U-shaped channel, pins are guided through the upper portion of the U-shaped channel. As each flight 42 leaves channel U, it assumes a generally horizontal position and supports the pin which it has been pushing through the channel. These pins are then carried upwardly through a vertical channel 62, formed by the side of rack housing 108, and the back and side of magazine

housing 25, to the triangularizing or rack section R of the magazine. A plate 63, provided with a curved portion 65 at its bottom end, extends upwardly along channel 62 and transversely across the top of the machine, as shown in Figure 2. Curved portion 65 tends to push any pin on a flight into proper position therein. Plate 63 maintains pins in proper position on flights 42 during the lifting movement and the rolling movement thereof along the top of rack R.

The preferred form of rack section R consists chiefly of two properly spaced, vertically mounted plates 64 (Figures 1 and 2), which are provided with ten pin locating or supporting stations 1 to 10 which form the same pattern and correspond exactly with the ten pin locating spots on the bowling alley bed. While ten stations are shown, obviously more or less could be provided to meet change of rules in the game. In facilitating the delivery of pins to the pin locating stations, several stations are connected by a common feed channel. Plates 64 are provided with four feed channels, namely, 66, 68, 70 and 72, each of which has an opening 74, 76, 78 and 80 respectively, leading to the top edges 82 of plates 64. The design of the rack section R is such that feed channel 66 connects and serves pin stations 1, 3, 6 and 10; feed channel 68 serves pin stations 2, 5, and 9; channel 70 serves pin stations 4 and 8, and channel 72 serves pin station 7. Each of the ten stations is provided with a pin arresting mechanism which consists of a pair of pin supporting lugs 84, 85 employed for the purpose of supporting the head and bottom portion of the pin in substantially horizontal position. Each pair of lugs 84, 85 consists of a rigidly mounted rear lug 85 and a hinge mounted front lug 84. Each lug, with the exception of the lugs for stations 1, 2, 4 and 7, is attached to a narrow arm 86 for pivotal movement about a horizontal pivot. Each pair of arms 86 is mounted on a shaft 88 pivotally supported by plates 64. Since stations 1, 2, 4 and 7 are located at the bottom of feeding channels 66, 68, 70 and 72 respectively, no rear pin supporting lug is necessary, but the bottom of each feeding channel in the rear plate is so formed as to provide a proper support for the bottom portions of the pins coming to rest in said stations. The front lugs 84, which support the neck portions of pins in stations 1, 2, 4 and 7, are hinge mounted on horizontal pivots in brackets 90 secured to the front side of the front plate 64. All front supporting lugs 84, in addition to being hinge mounted, are also equipped with a suitable tension spring 92, which normally biases them to vertical position, but yields to permit forward tilting of lugs 84 when a set of horizontal pins is extracted from rack R. On each shaft 88 is mounted a lever 94 (Figures 1 and 9) which by means of a link 96 is connected to a trip or control arm 98, each of which is pivoted on a shaft 102 supported by plates 64. Near the top portion of each of the feed channel openings 74, 76 and 78, is located a bell crank-shaped, spring-mounted check arm 104, each of which is pivoted on a horizontal shaft 106 supported by plates 64. Arms 104 are so designed that the lower portion 107 extends into pin locating stations 8, 9 and 10, respectively, when these stations are empty. As soon as a pin occupies one of these stations and presses downwardly against portion 107, the upper free end of the respective arm 104 is moved into a position such that it closes the upper opening of the respective feed channel and thereby prevents any successive passing pin from entering the same. Each arm 104 is provided with a tension spring 105 (Figure 9), employed for the purpose of preventing it from projecting into the feed channels when no pin is in its station.

The triangularizing or pin rack section R operates as follows: As pins carried by flights 42 of pin conveyor CO reach the top of channel 62 and adjacent to the top edge of the pin rack housing 108, pin conveyor CO

turns and moves in a horizontal direction, thereby causing flights 42 to assume a substantially vertical position. All pins which had been lifted by flights 42 are now pushed or rolled along the top edges of spaced plates 64 (Figure 1). As the conveyor chains 32 move horizontally, the cradles 42 are held vertically by means of their respective guide shoes 44 contacting suitable guide rails 110 secured to the top plate of housing 25 (Figure 1). When rack R is empty, the first pin rolled along top edges 82 of plates 64 will, upon reaching opening 74, due to its own weight, drop therethrough into feed channel 66 and come to rest at station 1, where it is held in the proper horizontal position by the pin supporting lugs 84, 85 of this particular station, described heretofore. On its way to station 1, the falling pin, of course, passes stations 3, 6 and 10, thereby temporarily depressing control arms 98 for the stations 6 and 10, and also check arm 104 at station 10, which momentarily effects a closing of opening 74 of feed channel 66. Upon reaching station 1, however, this pin depresses control arm 98 of station 3, which remains depressed so long as this pin remains in station 1. The depressing of this control arm 98 through link 96 and lever 94 causes lever 86 to swing supporting lugs 84, 85 of station 3 into operative pin supporting position in feed channel 66, so that the next pin dropping through opening 74 into feed channel 66 comes to rest and is positioned properly thereon at station 3. The second pin arrested at station 3 in turn keeps the control arm 98 of station 6 in a depressed position which causes pin supporting lugs 84, 85 of station 6 to swing into and remain in operative pin supporting position in feed channel 66. The third pin dropping into feed channel 66, therefore, comes to rest on these lugs at station 6, which in turn keeps the control arm 98 for station 10 in a depressed position, thereby effecting a raising and locking of the pin supporting lugs 84, 85 at station 10 into the feed channel 66, so that the fourth pin dropping into feed channel 66 comes to rest on said lugs of station 10. The fourth pin deposited in station 10, however, by engagement with arm portion 105, also causes the upper portion of check arm 104 to move into the center portion of the opening 74 of feed channel 66, thereby closing it and guiding any following pin, arriving at said opening, over the same and preventing any further pin from entering feed channel 66 (Figure 9). Since the opening 74 of channel 66 is thus closed, the following pins are moved by flights 42 along spaced edges 82 farther until they reach opening 76 of feed channel 68 where they drop into stations 2, 5 and 9 respectively in the same manner as the first four pins dropped into stations 1, 3, 6 and 10. The dropping of a pin in station 9 causes check arm 104 guarding opening 76 of channel 68 to swing into channel closing position in opening 76, thus preventing more pins from entering feed channel 68. Any following pins therefore are guided over the openings 74 and 76 to the edge of the opening 78 of the feed channel 70 which accommodates stations 4 and 8. After two pins drop through opening 78 into feed channel 70 in a manner similar to that described heretofore, stations 4 and 8 are filled and opening 78 is closed by means of the check arm 104 held in the center portion of said opening by the pin deposited in station 8. The remaining pin forwarded by the pin conveyor is guiding over the closed openings 74, 76 and 78 to the opening 80 of feed channel 72, the bottom of which forms the station 7. After the last pin is delivered to station 7, the loading of the triangularizing pin rack is completed; triangularized pins held therein are ready to be transferred by a suitable pin spotter to the alley. Since the pin deposited in station 7 is the last of the ten pins elevated by pin conveyor during any cycle, the opening 80 does not need a check arm as employed at the other openings 74, 76 and 78, and none is provided.

Stations 1 to 10 in the pin rack R are arranged in the

same manner and conform with the same pattern in which the pins are placed on the alley bed, i.e. station 1 corresponds with pin 1 on the alley, stations 2 and 3 correspond with pins 2 and 3, etc. After passing over the top of the pin rack section R, pin conveyor C makes a turn and moves vertically in a downward direction as indicated by the arrow in Figure 1. To save space and ready flights 42 to a pin receiving position when arriving at the bottom of housing 25, the flights, upon leaving the top portion of said housing, are moved or swung about their pivots from a vertical hanging position to a position where, in conjunction with bars 32 on chains 30, they form an almost flat conveyor band. The position of the flights or cradles 42 is changed by means of two studs 112 secured to the rear wall of housing 25 and protruding into the path of the cradles at the upper left turning corner of the conveyor chains 30. After flights 42 have been turned, guide shoes 44 of each flight engages with a vertical guide bar 114 attached to the inner wall of housing 25.

The pin setter table T (Figure 2) employed for the purpose of transferring the pins from the triangularizing pin rack R to the alley, consists of a suitable housing 120 in which are rigidly secured ten cylinders 122 arranged in the same manner and triangular pattern as the stations 1 to 10 in the pin rack R which correspond with the spots on the alley on which the bowling pins are placed. Since all cylinders 122 are identical in construction and operation, it is considered that a description of one will suffice for all. Each cylinder 122 carries a plurality of spring mounted gripper arms 124 which at one end suitably engage a cone shaped gripper actuating member 126 which is attached to one end of a rod 128 suitably supported in a sleeve or hub 130 mounted on a cylinder cover plate 132 which may form an integral part of cylinder 122. The other end of rod 128 is fastened to a plate 134 which at several suitable points engages with a number of threaded spindles 136, the ends of which are supported in bearings of suitable ribs or plates which may be an integral part of table housing 120. Each spindle 136 has secured to one end a sprocket 138, each of which by means of a chain 140, is connected to a sprocket 142, all of which are mounted on a shaft 144 protruding from a suitable reversible gear reduction motor 148 suitably secured within the table housing 120. It may be readily understood that the turning of spindles 136 through motor 148 causes plate 134 to move towards or away from the cylinder cover plates 132, which in turn moves each cone shaped member 126 on rod 128 in each cylinder towards or away from the ends of its respective gripper arms 124 thus effecting a gripping or releasing action of said gripper arms 124 in each cylinder 122.

Table T is provided with a pair of studs 150 (Figure 55) 2) swingably supported in a pair of arms 152 pivotally mounted on a horizontal transverse shaft 154 supported at each end in suitable bearings of two frame members 156, each of which is mounted on the upper portion of the inner wall of the bowling alley kickbacks. Arms 152 also carry a transverse shaft 158 to which, at each end adjacent the outside of each arm, is mounted a gear 160. Gears 160 engage with stationary gear segments 162, each of which is rigidly secured to the inner side of its respective frame member 156. Shaft 156 is rotated either clock or counter clockwise by one, or preferably two, reversible gear reduction motors 164, mounted on a sleeve bracket 166 loosely supported by transverse shaft 154. It may be readily seen that a clockwise rotation of shaft 158 causes gears 160 to move downwardly on the stationary gear segment 162, thus effecting a downward movement of arms 152 and consequently of pinsetter table T towards the alley bed, while a counter clockwise rotation of shaft 158 effects a raising of table T away from the alley bed.

Since the triangularized pins in pin rack section R are

arranged in a horizontal position, but have to be placed on the alley in a vertical or upright position, table T, in effecting the necessary transfer, is turned 90° by means of a pair of guide rollers 170, one of each of which is pivotally mounted on the exterior walls of table housing 120. Each roller 170 runs in a cam track 172 of a vertical cam plate 174 mounted on the inner side of the frame members 156. After a set of ten pins has been transferred by table T from rack section R to the alley bed, table T rises from its lowermost position I indicated in dotted lines (Figure 2) to a dwell position II above the alley and remains in this dwell position until the player has thrown a ball.

After a ball is thrown by the player, it rolls from an inclined platform 180 in the pit P onto a ball lift L (Figures 1, 2, 4 and 7) consisting of a rack 182 pivotally attached to a pair of lugs 184 mounted on a suitable frame within magazine M. The rack 182, which in the illustrated embodiment is made of tubular members, is so constructed as to provide an inclined transverse runway which leads into a delivery cradle consisting of tubular member 186 secured substantially at right angles to tubular rack 182, therefore, any ball rolling onto any portion of tubular rack 182 will thus gravitate to the junction of member 186 and rack 182. Adjacent one end of member 186 is attached one end of a tension spring 188. The other end of spring 188 is secured to a stud 190 (Figure 7) held by a suitable frame member of magazine M. Ball lift L is held at the bottom of pit P by the lower edge of a vertical backstop or pit cushion 192 secured to a pair of supporting brackets 194 (Figure 7). At the upper corner of each bracket 194 is pivoted a roller 196 running in a vertical cam track or guide channel 198 suitably secured to frame plates within the magazine housing 25. The lower corner of each bracket 194 is attached to a stud 202 which is an integral part of an endless chain 204, and which also carries a roller engaging in a vertical cam track 206. Both chains 204 are led over a pair of idler sprockets 208 and are driven or reciprocated by a pair of sprockets 210 mounted on a horizontal drive shaft 212 carrying a sprocket 214 (Figure 1) which is oscillated through a chain 216 running on a sprocket 218 mounted on a shaft projecting from a reversible reduction gear motor 220 suitably mounted on the outside wall of ball elevator housing 222. The machine is timed in such a manner that, as soon as a ball comes to rest in the rack 182, motor 220 actuates the driving sprockets 210 to move the endless chains 204 in counter-clockwise direction, thereby effecting a raising of the cushion 192 in the manner described above. The raising of cushion 192 in turn effects a release of ball lift L, which, due to the action of tension spring 188, swings it to the position indicated in dotted lines in Figure 7. Thus, since cushion 192 has continued its upward travel, the rocking movement of ball lift L causes a ball to roll onto member 186 and into or onto the ball elevator E, which elevates the ball in the elevator housing 222, and conveys it to a delivery chamber 223 formed in the top portion of housing 222. Chamber 223, of course, is closed so long as cushion 192 is in its uppermost position, indicated in dotted lines in Figure 7, but as soon as the reversible motor 220 turns sprockets in a clockwise direction, cushion 192 moves down again, permitting the ball to roll by gravity from exit chamber 223 onto a suitable transverse ball return runway 225 (Figures 1, 4 and 7) which delivers a ball onto a conventional return runway.

The ball elevator E (Figures 1, 4 and 7) consists of a pair of endless chains 228, each of which carries a plurality of suitably mounted, equally spaced ball supporting lugs 229 which are so arranged and positioned that each pair of opposing lugs 229 on the opposing chains form a cradle for a ball to be lifted. Each pair of opposing lugs 229 projects through a suitable vertical slot in spaced side walls of elevator housing 222, thus con-

fining the ball during elevation in the slot formed by two opposing lugs 229. As shown, the ball engaging portion of each lug is curved in order to conform to the curvature of a ball, and prevents damage thereto.

5 The elevator chains 228 are driven by means of a sprocket 230 on shaft 232 of motor 234. Sprocket 230 through chain 235 (Figure 7) drives a suitable sprocket mounted in shaft 238 supported in suitable bearing brackets attached to the outer wall of housing 222. Also 10 secured to shaft 238 is a sprocket 240 (Figure 1) which drives one of the endless elevator chains 228. The other elevator chain is driven by shaft 238 by means of a sprocket 242 mounted on a shaft 244 through a horizontal shaft 246 and suitable bevel gearing (not shown). Both 15 elevator shafts 228 run over a pair of idler sprockets 248 pivoted to shafts 250 supported in suitable bearing brackets attached to the outer wall of housing 222.

In case some pins remain standing after the first ball is thrown by the player, the table T descends, picks up 20 said standing pins and returns to its dwell position II above the alley (Figure 2) after which a suitable alley sweep S, which functions also as a guard against carelessly or inadvertently rolled balls, pushes the fallen pins into pit P. In order to assure that all pins falling or pushed 25 into pit P reach the lower chamber F of pin magazine M, pit P is provided with a suitable device for moving pins rearwardly in the pit. In the form illustrated, this is a pit sweep PS which pushes all pins from the pit onto the moving floor formed by flights 42 and bars 32 of the pin conveyor CO which runs in a substantially horizontal plane across the bottom of chamber F. Flights 42, while passing through the bottom portion of chamber F, move progressively into substantially horizontal portions and are held in that arrangement by means of their 30 guide shoes 44, which engage a guide rail 252 attached to the bottom portion of housing 25. A pin 253, projecting from the rear wall of housing 25 into the path of flights 42 near the turning point of the conveyor chains 30 (Figure 1), assures a proper guidance of shoes 44 onto guide rails 252.

Pit sweep PS (Figure 2) consists of a transverse sweep board 254 attached to a horizontal gear rack 256 which engages with and is reciprocated by a gear 258 mounted on shaft 259 protruding from a reversible gear reduction motor 260 conveniently mounted beneath the alley bed. 45 In order to provide greater stability to board 254, it may be attached to and reciprocated by two or more gear racks (not shown) which would necessitate two or more gears (not shown) mounted on common shaft 259 leading to said reversible gear reduction motor.

The alley sweep S employed (Figure 2) consists of a sweep board 262 extending across the alley and at its ends secured to arms 264. Arms 264 are pivotally attached to spaced endless chains 266 actuated by spaced oscillating sprockets 268 mounted on shafts 269 of reversible gear reduction motors 270. Each motor is suitably mounted to the respective frame member 156. Each chain 266 runs in a suitable channel in frame member 156. Each arm 264 is provided with a suitable double-acting shock absorber rod 272 linking arm 264 with chain 266. This mechanism provides means which soften any sharp impact which sweep board 262 may receive when fallen pins are swept into the pit. This mechanism also absorbs the shock caused by carelessly or inadvertently thrown balls striking against the front face of sweep board 262. It is to be understood, of course, that the two motors 270, activating the sweep S, are fully synchronized and act as one unit.

70 While the triangularizing pin rack R, illustrated in Figures 1, 2 and 9 and described heretofore may be considered the preferred form of pin rack construction, a modified form of pin rack R' is disclosed in Figures 3, 5, 6 and 8. In this modified form, pin rack R' consists of a frame or shell 280 in which are supported four shelves 75 282, 284, 286 and 288, each of which carries one or more

sets of laterally spaced upright mounted pin guide plates 290. The side edges of plates 290 are spaced in such a manner as to form pockets or stations arranged in a manner similar to the ten stations in plates 64 of the preferred form illustrated in Figure 1 and correspond with the pattern in which the pins are set on the alley. As shown in Figure 8, the several sets of station forming plates are also spaced longitudinally in order to engage bowling pins at two points in order to locate and hold them properly in substantially horizontal positions for removal from rack R'.

The arrangement of plates 290 is such that on shelf 288 is located station No. 1 for No. 1 pin, on shelf 286 are located stations Nos. 2 and 3 for Nos. 2 and 3 pins, on shelf 284 are located stations Nos. 4, 5 and 6 for the Nos. 4, 5 and 6 pins, and on shelf 282 are located stations Nos. 7, 8, 9 and 10 for pins Nos. 7, 8, 9 and 10. With the exception of station No. 1, each station is provided with a gap closing device. In stations Nos. 7, 8, 9 and 10, each device consists of a control arm 292 mounted on a shaft 294 supported in suitable bearings in front and rear guide plates 290. To each shaft 294 is also secured a pair of control lugs 296, each of which engages with one of the two gap closing arms 298, which are pivoted on a shaft 302, also held by guide plates 290. Due to the difference in construction, i.e. the difference in depth of the pockets forming stations Nos. 2, 3, 4, 5 and 6, from that of pockets forming stations Nos. 7, 8, 9 and 10, each of the former pockets is provided with a pair of control arms 304 each of which is mounted on a shaft 306 supported in suitable bushings or bearings in guide plates 290 (Figure 8). To each shaft is secured a pair of control lugs 308, each of which engages with a gap closing arm 310, pivotally mounted on shaft 312 supported on bearings in front and rear plates 290. Control arms 304 and gap closing arms 310 are of similar shape and design as arms 292 and 298 respectively, but shorter in length. These arms are shown in greater detail in Figures 5 and 6. While Fig. 5 illustrates a deeper pocket than those employed in stations Nos. 7, 8, 9 and 10, Figure 6 discloses a shallow pocket as used in stations Nos. 2, 3, 4, 5 and 6.

The modified stations shown in Figures 5 and 6, differ from the pockets illustrated in Figures 3 and 8 only in the contour or shape of the side edges of the vertical guide plates 290 forming said pockets. In Figures 5 and 6, the sides are shown straight, while in Figures 3 and 8 the sides are shown curved. Both types of stations work equally well in receiving and supporting pins.

The pins are elevated by flights 42 to the top edges 314 of vertical guide plates 290 (Figure 3) in the same manner as in the preferred form illustrated in Figure 1, and described heretofore. The first pin delivered to top edges 314 is rolled horizontally over or along the same by the vertically positioned flight until the pin encounters the first pocket forming No. 10 station. The pin drops into this pocket and comes to rest on the shelf 282 in a head forward horizontal position. By dropping into and while occupying said station, this pin depresses control arm 292 which heretofore protruded into station No. 10. Control arm 292 in turn actuates control lugs 296 which in turn effect an upward movement of gap closing arms 298, bringing the latter substantially in line with the top edges 314 of plates 290, thereby forming a bridge closing the pocket and preventing any further pin from dropping into station No. 10. The second pin arriving at the top edges 314 of plates 290 is rolled horizontally therealong over the bridging gap closing arms 298 of station No. 10 and into the open pocket of station No. 9, causing a depression of the respective control arm 292 which effects the closing of this pocket by its respective gap closing arm 298 in the same manner as the gap closing mechanism for station No. 10 described above. The third and fourth pins will be delivered into the pockets of stations Nos. 8 and 7 respectively, each of which is

closed in the same manner after the arrival of a pin therein. The fifth pin, therefore, is rolled by its flight 42 over the top edges 314 and the closed pockets of stations Nos. 10, 9, 8 and 7 until it reaches the edges of the extreme left guide plates 290 on shelf 282 (Figure 3) where it falls into a chute formed by the side edges 320 of said guide plates and the inner wall of shell 280. The curved top edges 322 of the extreme left side guide plates 290 on shelf 284 guide the fall of the pin and bring the same in contact with a pair of horizontally mounted longitudinally spaced rotating spirals 324 (Figures 3 and 8) which engage said pin at spaced peripheral points on its top portion and roll the same over the top edges of guide plates 290 on shelf 284 until it reaches and drops into the pocket of station No. 4. The arrival of a pin in the latter, causes control arms 304 to be depressed. This in turn, through control lugs 308, effects a movement of gap closing arms 310 to pocket closing position. The sixth pin delivered by flight 42 to the top edges 314 will follow the same path as the fifth pin, except that by means of spirals 324, it is moved over the now closed pocket of station No. 4 and drops into the pocket of station No. 5 (Figure 8). The seventh pin is moved over the same path as the two previous pins and is dropped into the pocket of station No. 6. The eighth pin is moved in the same manner over the top edges of plates 290 on shelves 282 and 284 until it reaches the extreme right side edges 326 of plates 290 on shelf 284, where it drops into a chute formed by side edges 326 and the curved top edges 328 of plates 290 on shelf 286. The curved top edges 328 guide the top portion of this pin into engagement with a pair of horizontally mounted longitudinally spaced rotating spirals 330 which advance it until it drops into the pocket of station No. 3. After receiving a pin, the pocket of station No. 3 is closed in the same manner and by mechanisms identical with those used in closing the pockets of stations Nos. 4, 5 and 6. After being delivered to the top edges 314, the ninth pin follows the same paths as the previous pin and is then dropped in the pocket of station No. 2. The tenth and last pin is moved in the same paths and by the same mechanism as the two previous pins until it reaches a chute formed by the extreme left side edges 332 of plates 290 on shelf 286 and curved top edges 334 of guide plates 291 vertically mounted on shelf 288. Curved top edges 334 guide the top portion of said pin into engagement with a pair of horizontally mounted longitudinally spaced rotating spirals 336 which advance this pin until it drops into the pocket of station No. 1, thus completing the filling of the triangularly arranged stations Nos. 1 to 10 with pins.

Spirals 324, 330 and 336 are driven by means of a suitable gear reduction motor 338 (Figure 3) conveniently mounted on the inner side of shell 280. The shaft of motor 338 carries a sprocket 340 which, through chain 342, drives sprocket 344 mounted on a horizontal shaft 346 supported by suitable bearing brackets conveniently attached to housing 25 of the machine. Also secured to shaft 346 are sprockets 348 and 350. The latter, through chain 352, drives sprocket 354 mounted on shaft 356 which carries one of the two spirals 330. Sprocket 348, through chain 358, drives sprocket 360 mounted on shaft 362 which carries one of the two spirals 336. Shaft 362 also carries sprocket 364 which, through chain 366, drives sprocket 368 mounted on shaft 370 which carries one of the spirals 324. The drive for one of each pair of spirals 330, 336 and 324 just described, refers to the spirals located towards the front portion of pin racks. The drive for each rearwardly located spiral is the same with the exception that it is driven from a shaft (not shown) which is in line and parallel to shaft 346 and is driven by the latter through a suitable pulley (not shown) and belt 372 from a pulley 374 mounted on shaft 346. In arranging belt 372 to run crosswise, a clockwise and counter clockwise rotation of the front and rear spirals respectively is obtained.

An important feature of this invention is the pin changing mechanism which includes a storage bin B (Figure 1). In the embodiment shown, bin B is designed to hold twenty pins or two full sets. If desired, however, fewer pins can be stored therein. The pin changing mechanism is so constructed and operated that bowling pins in play can be transferred from the alley and rack R to storage bin B and exchanged for stored pins in bin B. The pin changing and storage mechanism is employed for changing and/or replacing one or more sets of pins in use or in play for one or more sets of pins in storage in bin SB. For example, if there are two sets of pins in storage bin SB, and two sets of pins are in play, it is possible to change one set progressively and in this way extend the life of each set of pins. In this manner, a saving results to the bowling alley proprietor because of the longer use which he obtains from his bowling pins.

It is also quite common in bowling alley establishments to use "open play" pins whenever possible instead of new or relatively new "league" pins which are required in league or tournament play. The term "open play" as applied to bowling pins, includes pins which although worn or in use for some time and not acceptable for league play, can still be used and are not objected to by many bowlers. It will be seen, however, that although "open play" pins can be used at certain times, it may be necessary or desirable in order to satisfy customers, to change the pins. The mechanism described hereinafter accomplishes this purpose in a rapid and efficient manner.

The storage bin designated generally SB, consists of a suitably shaped box or shell 380 mounted within housing 25 adjacent the pin reversing and orienting channel U. Within the box 380, are suitably arranged a number of spaced generally horizontally positioned shelves 382 having a slight incline which support bowling pins delivered into box 380, and along which pins can roll by gravity and pressure of succeeding pins to proper storage positions, such as shown in Figure 1. The top portion of box 380, adjacent channel U, is provided with a hinge mounted entrance or guard door 384, which is normally maintained in bin entrance closing position by spring 385. Door 384 is moved to bin entrance opening position by means of a solenoid 388 suitably mounted on the top of said box 380. The armature of solenoid 388 is pivotally connected to one end of link 386. The other end of link 386 is connected to door 384. When door 384 is in bin opening position, bowling pins being pushed through channel U by flights 42 are delivered into bin SB. These pins gravitate downwardly between plates 389, 391, and 393 and roll from shelf to shelf through passageways formed by the ends of shelves 382 until all pins delivered into bin SB take positions as shown in Figure 1. While shelves 382, when provided with a slight incline (Figure 1) perform satisfactorily, their inclination can be varied as desired in order to control movement of pins therewith.

In order to provide for the delivery of stored pins from bin B, the bottom portion of box 380 is provided with a hinge mounted exit or trap door 390. The latter, through link 392, is connected to the armature of a solenoid 394 suitably attached to the lower side of box 380. Door 390 is provided with suitable spring 391 employed for the purpose of keeping it closed when not actuated by its solenoid 394. Adjacent the entrance and exit of box 380 are mounted suitable pin counters 396 and 398 respectively, the function of which will be described herein-after.

Counters 396 and 398 can be similar in design and construction to those disclosed and described in Rundell Patent No. 2,388,707, issued November 13, 1945.

In order to make clear the operation of the pin changing and storing mechanism, the automatic transfer of twenty pins or two sets of say, "open play" pins from the pin rack R or R' and alley to storage pin B and the replacement thereof of twenty pins or two sets of, say

"League" pins is described as follows: Reference is made to Figures 10 to 17 inclusive, which disclose a step by step operation of the pin storing and changing mechanism.

It is assumed that pins designated A and B represent two complete sets of open play pins, and pins designated C and D represent two complete sets of league pins, and, before starting the machine, pins B are on the alley and pins A are in the pin rack, while pins C and D are stored in storage bin SB. Table T rests in its dwell position (Figure 10). Upon operating a suitable pin transfer switch, which will be described hereinafter, pins A on the alley are swept by alley sweep S into pit P, while table T ascends and removes pins A from pin rack R (Figure 11.) Table T then places pin A on the alley while trap door 390 of the storage bin is opened by its solenoid allowing pins D to roll out of said storage bin into lower chamber F onto the moving pin conveyor which elevates pins D upward to the now empty pin rack R (Figure 12). After the tenth pin of set D has passed the pin counter 398, the latter effects a closing of trap door 390 of storage bin SB. Due to their weight and the slight incline of shelves 382 in the storage bin, pins C have followed the outgoing set D, but are prevented from leaving storage bin SB by the timely closing of trap door 390. Table T in the meantime has ascended to its dwell position and the entire set of pins D is conveyed into pin rack R while the set of pins C remains in pin storage SB (Figure 13). The pit sweep PS then swings into action and sweeps pins B from the pit P into lower chamber F onto the moving pin conveyor 30. Meanwhile, due to the action of solenoid 388 the entrance door 384 on top of the storage bin opens, thus allowing pins B, carried upward by flights 42 of pin conveyor 30, to be delivered into storage bin SB on top of set of pins C, which at this time remain in the storage bin. After the pit sweep PS sweeps pins B into the lower chamber F onto the pin conveyor, sweep S sweeps pins A from the alley into pit P, while the table T extracts the pins D from the pin rack R and holds them in readiness for spotting above the alley (Figure 14). After the tenth pin of set of pins B has passed counter 386 at the entrance to storage bin SB, counter 386, through solenoid 388, effects a closing of entrance door 384, after which table T places the set of pins D on the alley and the trap door 390 at the bottom of the storage bin again opens and allows pins C to drop onto the moving pin conveyor 30 which elevates them and delivers them to pin rack R (Figure 15). In the meantime, the now empty table T ascends and remains in its dwell position above the alley. As soon as the tenth pin of set of pins C passes counter 398 adjacent trap door 390, the latter, through its solenoid 394, is closed again and prevents any further pin leaving storage bin SB. The complete set of pins C, of course, is elevated to the pin rack R (Figure 16). Pins A, still resting in the pit, are then swept by pit sweep PS into lower chamber F onto the moving pit conveyor. In the meantime, entrance door 384 opens again and pins A, elevated by the pin conveyor, are delivered into storage bin SB on top of set B already located therein. After the tenth pin of set of pins A passes counter 386 at entrance door 384, the latter is closed in the manner described above, and the change of two entire sets of pins is completed (Figure 17). Pins A and B which heretofore were on the alley and in rack R respectively, are now in the storage bin, and sets of pins C and D, which heretofore were in the storage bin, are now in rack R and on the alley, respectively.

In order to properly control the action, as well as the timing of the various mechanisms during a normal as well as a pin changing cycle, the machine is provided with a suitable electrical control system, such as shown in Figure 18.

The normal cycle of the machine starts when a ball, rolled by a player, lands on plate 180 in pit P, which causes a temporary closing of pit switch 402. This op-

eration starts gear reduction cam motor 404 (Figure 18). A shaft 406, protruding from motor 404, carries a number of cams, all of which are employed for the purpose of effecting the starting and stopping of the various operating mechanisms, as well as the proper sequence and timed relation of the same.

As mentioned heretofore, each mechanism is driven or actuated by its individual motor. As shown in the drawings, seven individual conventional gear reduction motors are employed. Five motors are of the reversible type; the other two are of the one direction rotating type. In order to properly control the direction of rotation as well as the time of rotation of each motor, the current supply is directed as well as timed by means of a cam designed to open or close properly arranged contacts. Therefore, alley sweep motor 270 is controlled by cam 408, pit sweep motor 260 is controlled by cam 410, table motor 164 is controlled by cam 412, pin gripper motor 148 is controlled by cam 414, ball lift and cushion motor is controlled by cam 416, pin conveyor motor 40 is controlled by cam 418 and ball elevator motor 234 is controlled by cam 420. Cams 408, 410, 412, 414, 416, 418 and 420 are mounted on shaft 406 of motor 404.

Also attached to shaft 406 is a motor control cam 422 which is used to keep cam control motor 404 running after it is started by the closing of pit switch 402. Cam 422 on shaft 406 starts turning in the direction of the arrow as soon as the temporary closing of pit switch 402 starts motor 404, causing cam follower 424 to ride off the high spot 426 of cam 422, which effects a closing of contacts 428, and a shunting of pit switch 402. One side of switch 402, as well as one side of contacts 428 is connected to one of the power lines L by means of a line 430. The latter is provided with a normally closed switch 432, the action of which will be described hereinafter.

As cam shaft 406 begins to rotate a high spot 433 on ball and cushion lift cam 416 engaged by cam follower 434 on switch arm 435, throws reversing switch 436 to the right, as viewed in Figure 18, and through proper contacts, causes reversible gear reduction motor 220 to turn in a counter-clockwise direction, thereby effecting a raising of the backstop or cushion 192, which allows spring powered ball lift L to rise and deliver the ball to ball elevator E. At this time, the cam follower 434 of switch 436 has dropped from the high portion 433 of cam 416 to a neutral surface 438 of the same, causing switch 436 to resume its neutral position which shuts off the power to motor 220 and causes it to stop, thereby allowing cushion or backstop 192 to remain in its raised position. In the meantime, a high portion 440 on cam 420 has engaged cam follower 442 of switch 444 and closed it. The closing of switch 444 starts motor 234 which drives vertical ball elevator E, thereby elevating the ball through elevator shaft 222 to exit 223 for delivery onto return runway 226. Motor 234 and hence elevator E, stop again as soon as cam follower 442 drops off high spot 440 of cam 420 effecting the opening of switch 444.

Shortly after a bowling ball is thrown and lands in pit P, table control cam 412, through a cam follower 446 dropping into a low spot 448 on cam 412, causes a reversing switch 450 to move to the left, as viewed in Figure 18, from a neutral to a circuit closed position, thereby starting reversible gear reduction motor 164 and effecting a downward movement of the table T from its dwell position II above the alley to its pin gripping position I adjacent the alley (Figure 2). As soon as table T arrives at its pin gripping position I, table control cam 412 throws reversing switch 450 back to its neutral position, thus effecting a stoppage of motor 164, and table T. As soon as table T comes to rest at its pin gripping position, a high spot 452 on pin gripper control cam 414 through cam follower 454, throws a reversing switch 456 from a neutral to circuit closing position. This starts reversible gear reduction motor 148 which actuates the pin gripper mechanism in table T

(Figure 2) and causes grippers 124 to grip any pins remaining standing on the alley. Cam 414 is designed in such a manner as to allow sufficient time for pin grippers 124 to grip the standing pins securely. Continued rotation of cam 414 then causes reversing switch 456 to be thrown from its previously described circuit closing position to its neutral position, which stops pin gripper motor 148.

Table control cam 412 is so designed and timed that, as soon as pin gripper motor 148 stops, a high portion 458 of this cam, through follower 446, throws switch 450 from a neutral to a circuit closing position. Since at this time switch 450 is moved by high portion 458 of cam 412 to the right, as viewed in Figure 18, the flow of current to table motor 164 is reversed, thus causing motor 164 to effect an upward movement of table T, carrying the pins held by the pin gripper mechanism described heretofore. Table control cam 412 is so designed that as soon as table T reaches its dwell position II above the alley, cam follower 446 drops off the high spot 458, causing switch 450 to snap into neutral position and thereby stops motor 164.

As soon as table T reaches its dwell position II, a high spot 460 on alley sweep cam 408, through cam follower 462, throws a switch 464 from a neutral position to a right side contact, as viewed in Figure 18. This causes reversible gear reduction motor 270 to start, thereby effecting movement of alley sweep S towards pit P, causing all pins which were knocked down by the ball and which have fallen onto the alley or into the gutter, to be swept into pit P. As soon as alley sweep S reaches the end of the alley, cam follower 462 drops from high spot 460 of cam 408 to low spot 466 thereon, causing switch 464 to move from its right side contacts to its left side contacts. This movement causes a reversing of motor 270 and hence the return movement of sweep S. As soon as the latter reaches its inoperative position above the alley, cam follower 462 rides from low spot 466 onto neutral surface 468, which causes switch 464 to break its contacts and move to its normal neutral position, thereby stopping motor 270.

As soon as the fallen pins have been swept into pit P by alley sweep S, a high spot 470 on pit sweep control cam 410, through cam follower 472, moves a switch 474 to its right side contacts (see Figure 18), causing reversible gear reduction motor 260 to rotate in the proper direction to effect a forward motion of pit sweep PS. In this manner, all pins previously swept into pit P are moved into the lower pin receiving chamber F onto the pin conveyor CO which is set in motion by high spot 476 on pin conveyor control cam 418 which through cam follower 478, closes a switch 480 and starts the pin conveyor motor 40. The back-stop or cushion 192 and the ball lift L, as previously described, are still in their uppermost positions. In order to prevent the pins pushed onto the pin conveyor CO from tumbling off the same and out of chamber F when conveyor CO starts moving, pit sweep PS, after reaching its forwardmost position at the rear of the pit, stops and dwells adjacent to the conveyor for a short period of time, after which pit sweep PS returns to its original position. The stoppage of pit sweep motor 260 is caused when cam follower 472 drops from high spot 470 of cam 410 to a neutral portion thereof, which breaks the right side contact of switch 474 and returns the latter to its neutral position. After remaining for a short period of time on the neutral portion of cam 410, cam follower 472 drops into low spot 482 thereon, causing switch 474 to be moved into engagement with its left side contacts, thus reversing the flow of current to motor 260 and effecting a return motion of pit sweep PS. After the latter reaches its inoperative position adjacent the end of the alley bed, as shown in Figure 2, cam follower 472 rides from low spot 482 onto the neutral surface of cam 410, causing

switch 474 to return to its neutral position and stop motor 260.

As soon as pit sweep PS starts its return movement, cam follower 434 of switch 436 drops into low portion 437 of ball and curtain lift control cam 416, the action of which moves switch 436 into engagement with its left side contacts (see Figure 18), causing motor 220 to start and effect the downward movement of back-stop 192 and ball lift L. Upon reaching their lowermost positions, cam follower 434 rides onto the neutral surface of cam 416, again causing switch 436 to move back to its neutral position. This action stops motor 220. Pin conveyor CO continues running until cam follower 478 of switch 480 drops from high spot 476 of cam 418 to the neutral surface of the same, thereby opening switch 480 and stopping the conveyor motor 40. In the meantime, and as soon as alley sweep S has returned to its inoperative position above the alley, cam follower 446 drops into low spot 484 of table control cam 412, causing switch 450 to engage with its left side contacts, as viewed in Figure 18. This operation causes table T, carrying the previously picked up pins, to descend and replace them on the alley. When table T reaches its lowermost position I, cam follower 446 rides from low spot 484 onto a neutral portion of cam 412, thereby moving switch 450 back to its neutral position which effects a stoppage of motor 164. Cam follower 446 rides on a neutral portion of cam 412 for a short period of time, resulting in a dwelling of table T at position I. During this time pin gripper motor 148 is set in motion to operate grippers 124 and release pins held thereby for respotting on the alley. Motor 148 is set in motion when cam follower 454 moves onto low portion 486 of cam 414, causing switch 456 to engage with its left side contacts, as viewed in Figure 18. After pin grippers 124 are opened fully, cam follower 454 rides onto a neutral portion of cam 414 again causing switch 456 to return to its neutral position, and thereby stop pin gripper motor 148. As soon as the respotted pins are released, cam follower 446 rides off the neutral portion of cam 412 onto a high spot 488 of the same, causing switch 450 to engage with its right side contacts, as shown in Figure 18, starting motor 164 and effecting an upward movement of table T to its dwell position II above the alley. The upward movement of table T stops as cam follower drops from the high spot 488 of cam 412 to a neutral surface thereon.

After the pins are respotted on the alley and table T has resumed its original dwell position II, a high part 427 on cam shaft motor control cam 422 engages with cam follower 424 on switch arm 429 and effects an opening of contacts 428, thereby causing gear reduction motor 404 and cam shaft 406 to stop. High portions 426 and 427 on cam 422 are exactly 180° apart, thus stopping the cam control motor 404 and cam shaft 406 every one-half revolution. Therefore one complete revolution of cam shaft 406 represents the first and second cycle of the machine which corresponds with the first and second ball thrown by the player.

After the first cycle, described above, is completed and high spot 427 on cam 422 has opened contacts 428, the machine is ready for the second cycle. At the end of the first cycle, every mechanism is in its normal position, the table dwells in position II above the alley and all pins which remained standing after the first ball was thrown, are standing on the alley.

The second cycle starts as soon as the second ball, thrown by the player, lands in the pit and causes a closing of pit switch 402. All control cams, with the exception of table control cam 412 and pin gripper control cam 414, are symmetrical, i.e. the high and low spots thereon for the second cycle are in the same sequence and time relation as during the first cycle. The second half of the table control cam 412 is so designed

as to effect an upward movement of table T after the second or last ball of a frame is thrown and not a downward movement to pick up pins as in the first cycle. During its movement upward in the second cycle, the table turns 90° and partly enters the pin magazine M, as shown in Figure 2, while the open pin grippers carried by said table, slide over the projecting neck portions of a set of pins supported horizontally in triangularizing pin rack R. During a short dwell period of table T, pin gripper control cam 414 effects the operation of grippers 124 to grip the pins after which the table moves away from rack R, removing the set of pins gripped by grippers 124. In its further movement, table T descends, turns again 90° during its downward movement and spots the new set of pins on the alley. Of course, the delivery of a new set of pins to the alley takes place after the latter has been swept clean of all standing and fallen pins by sweep S and the sweep has returned to its normal inoperative position above the alley. In the meantime, all pins of the previous or first set of pins are conveyed to the triangularizing pin rack R and the ball returned to the player in the same manner as during the first cycle of the machine, the first and second cycle representing the customary two balls or one complete frame in ten pin bowling.

In order to take care of a "strike" cycle, when all pins are knocked down by the first ball of a frame, an additional set of suitable control cams (not shown) may be employed to eliminate unnecessary delay in placing a new set of pins on the alley as soon as the pins of the previous set fall and/or are swept into the pit.

In addition to the control cams provided for the normal operation of the bowling pin setter just described, the machine is equipped with an additional set of control cams 502, 504, 506, 508, 510, 512, 514, 516 and 518 (Figure 18) employed for the purpose of controlling the time and sequence of operation of the various mechanisms when it is desired to replace or change sets of pins, as mentioned hereinabove. For example, it may be desired to change one set B presently on the alley, and another set of pins A in the pin rack R, for two sets of pins C and D presently in the storage bin SB, and convey the former two sets A and B into the storage bin.

The pin change control cams 502, 504, 506, 508, 510, 512, 514, 516 and 518 are mounted on a shaft 520 operated by a suitable gear reduction motor 522. In order to change sets of pins as outlined above, the player presses a push button 524 which starts the gear reduction motor 522. As cam shaft 520 begins to turn, a cam follower 526 on a switch arm 528 drops off a high spot 530 of motor control cam 502, causing switch arm 528 to close contacts 532. This shunts push button 524, and assures a continuous running of motor 522 after the release of the normally open push button 524. Motor 522 keeps on running until motor control cam 502 makes one full revolution, and cam follower 526 of switch arm 528 again runs on high spot 530 which breaks contacts 532 and stops motor 522. No ball is rolled down the alley either at the beginning or during the pin changing operation. Pit switch 402 is rendered inoperative at the beginning of the pin changing cycle when an arm 536 mounted on and turning with cam shaft 520 effects an opening of the normally closed switch 432 in line 430. This arrangement prevents starting of machine cam control motor 404 at any time during the pin change cycle.

When cam shaft 520 begins to turn, high spot 538 on alley sweep control cam 506 engages cam follower 540 on a switch 542 causing the latter to move from its neutral position into engagement with its right side contacts, as shown in Figure 18. This starts reversible alley sweep motor 270, whereupon alley sweep S sweeps the pins of set B from the alley into pit P. As cam follower 540 of switch 542 drops from high spot 538 of cam 506 into low spot 544 thereof, switch 542 is thrown into en-

gagement with its left side contacts, as viewed in Figure 18, which causes motor 270 to reverse its motion, thereby effecting a return movement of sweep S to its normal position. Motor 270 stops as cam follower 540 rides from low spot 544 onto the neutral portion of cam 506 which causes switch 542 to break its contacts and move to its neutral or open circuit position.

As soon as alley sweep S starts on its return stroke, high spot 546 on table control cam 510 contacts cam follower 548 of switch 550, causing the latter to move from its neutral position into engagement with its right side contacts, as viewed in Figure 18, thereby starting table motor 164 and effecting an upward movement of table T. The latter stops and comes to pin receiving position in front of pin rack R when cam follower 548 of switch 550 drops from high spot 546 to a neutral portion of cam 510, causing switch 550 to move to its circuit opening position which stops table motor 164. During this dwell period of table T, pin gripper cam 508, through high spot 552 and cam follower 554, actuates a switch 556 which starts pin gripper motor 148 in motion and effects an engagement of the pin grippers 124 in table T with the necks of pins of set A resting in pin rack R. After these pins are firmly gripped, pin gripper motor 148 stops as cam follower 554 drops from high spot 552 onto a neutral portion of pin gripper control cam 508. Table T, due to the action of low spot 558 of cam 510 upon cam follower 548 of switch 550, then moves away from rack R withdrawing the pins of set A and descends with them toward the alley. Upon reaching its lowermost position I, these pins are placed on the alley and the table movement is arrested as cam follower 548 of switch 550 rides from low spot 558 to a neutral portion on cam 510, thereby stopping table motor 164. A low spot 560 in pin gripper control cam 508 through cam follower 554 on switch 556 then sets pin gripper motor 148 in motion again and effects a release of pins A from grippers 124 in table T. After these pins are released, cam follower 554 of switch 556 rides from low spot 560 onto a neutral portion of cam 508 and stops pin gripper motor 148. Table T, through high spot 562 on the control cam 510 acting upon cam follower 548 of switch 550, then ascends again and dwells as position II above the alley as cam follower 548 of cam 550 drops from the high spot 562 onto a neutral portion thereof.

In the meantime, a high spot 564 on exit gate control cam 518 engages cam follower 566 of switch arm 568 which causes a closing of contacts 570 and the energization of solenoid 394 which, in turn, through its armature and link 392 effects an opening of exit gate 390. As soon as exit gate opens, the pins of set D, stored in the bottom portion of the pin storage bin SB, are discharged therefrom. The pin resting on gate 390 falls clear of storage bin SB when gate 390 opens. The remaining pins of set of pins D roll one by one along downwardly inclined shelves 380, 382 and fall one by one into chamber F and upon the substantially horizontally positioned flights 42 of moving pin conveyor CO which carries these pins directly up to the now empty pin rack R. The movement of pins of set D out of storage bin SB also results in the movement of pins of set C therein into the positions formerly occupied by the pins of set D, see Figure 12. Pin conveyor CO is set in motion shortly after cam shaft 520 starts turning, and remains in motion to almost the end of the pin changing cycle. Pin conveyor motor 40, during the cycle, is controlled by cam 514 on which runs cam follower 572 on switch arm 574 which opens and closes contacts 576 in order to effect the stopping and starting of the motor.

In order to prevent more than ten pins dropping out of storage bin SB, a pin counter 398 is located in a suitable position adjacent exit gate 390. Counter 398 may be similar in construction to that disclosed in Patent 2,388,707, issued November 13, 1945, to R. E. Rundell.

Counter 398 consists chiefly of a ten-tooth ratchet wheel 578 pivotally supported on a stud 580. Also pivotally mounted on stud 580 is a counter arm 582 which extends into the path of pins leaving storage bin SB. Arm 582 is provided with an extension lever 584 carrying a pawl 586 which is held in engagement with ratchet wheel 578 in a well known manner by a suitable tension spring (not shown). Suitably mounted on ratchet wheel 578 is a bridge plate 590 which normally joins a pair of contacts 592 connected to the current supply line of cam control motor 522. Counter 398 is designed in such a manner that ratchet wheel 578 rotates a distance of one tooth each time pin moving out of storage bin SB temporarily depresses counter arm 582. A suitable tension spring 588, attached to lever 584, is provided to return arm 582 to its normal position after depression. A suitable stop pin 589 limits the return movement of arm 582. A second spring, mounted pawl 594, engaging with ratchet wheel 578, is employed to prevent backlash of the latter.

As soon as the first pin of set D, dropping out of the storage bin SB actuates counter arm 582, ratchet wheel 578 advances one tooth. Since bridge plate 590 is mounted on the ratchet wheel, this causes an opening of contacts 592 and stops cam control motor 522. Stopping the latter, of course, effects the stopping of cam shaft 520 and all control cams mounted thereon, but, since the high spot 564 through cam follower 566 on switch arm 568 holds contacts 570 closed when control motor 522 is stopped, contacts 570 remain closed and therefore solenoid 394 remains energized. Consequently, exit gate 390 remains open, and the ten pins of set D move and drop from storage bin SB. Since cam follower 572 of switch arm 574 also is on the high portion of pin conveyor control cam 514, contacts 576 also remain closed and pin conveyor CO continues to move and conveys the pins D to triangularizing rack R where they are triangularized. All other cam followers at that moment are on neutral portions of their respective cams, and therefore no other mechanisms are in motion during this period. As the tenth pin of the pins of set D emerges from storage bin SB and depresses counter arm 582, the bridge plate 590 has, after the ten stepwise movements of ratchet 578, returned to its original circuit closing position, and again connects contacts 592 which immediately causes control motor 522 to start again. The starting of motor 522 effects a turning of exit control gate cam 518, whereupon cam follower 566 drops off high spot 564 and effects a breaking of contacts 570. The breaking of the latter effects a de-energization of solenoid 394, enabling spring 391 to close exit gate 392 and preventing the pin of set C, in this instance, from being removed from storage bin SB.

At this moment, there are a set of pins A standing on the alley, a set of pins B still lying in the pit, a set of pins C arrested in the storage bin SB and a set of pins D triangularized resting in the pin rack R (Figure 13). A high spot 604 on cushion lift control cam 512, through cam follower 606 on a switch 608, causes an engagement of the latter with its right side contacts, as viewed in Figure 18, thus starting motor 220 and effecting an upward movement of cushion 192 in order that pins of set B can be swept from pit P into chamber F onto conveyor CO. The upward movement of backstop 192 is checked as soon as cam follower 606 drops from high spot 604 onto a neutral portion of cam 512, again causing switch 608 to return to its neutral position.

As soon as backstop 192 has been raised in the manner described, a high spot 596 on pit sweep control cam 504, through cam follower 598, engages switch 600 with its right side contacts, as illustrated in Figure 18, thereby starting pit sweep motor 260 and causing pit sweep PS to sweep pins B from pit P beneath backstop 192 into chamber F onto moving pin conveyor CO. As cam fol-

lower 598 of switch 600 drops from high spot 596 via a neutral to low spot 602 of cam 504, motor 260 reverses and a return stroke of pit sweep PS is effected. Pit sweep motor 260 is stopped again as soon as cam follower 598 on switch 600 rides from the low spot 602 onto a neutral portion of cam 504.

Cushion 192 remains in its lifted position until pins B are swept into chamber F, after which a low spot 610 on cam 512 is engaged by cam follower 606, switch 608 is moved into engagement with its left contacts, as viewed in Figure 18, to start motor 220 and a downward movement of backstop 192 is effected. This downward movement stops as cam follower 606 rides from low spot 610 onto the neutral portion of cam 514 again, thereby breaking the motor circuit.

Since pin conveyor CO moves continuously, pins of set B, as soon as they are swept by sweep PS into chamber F, are carried upwardly for delivery to rack R. In the meantime, high spot 612 on the cam 516 is engaged by cam follower 614 on a switch arm 616, causing the latter to close contacts 618 and effecting an energization of solenoid 388. The energization of solenoid 388 through its armature and line 386, causes the opening of storage bin infeed gate 384 so that all pins of set B, while being conveyed through the U-shaped channel U by pin conveyor CO, are moved one by one through open gate 384 into pin storage bin SB. These pins, which are horizontally positioned, roll and/or slide along inclined shelf 387, 393 and 382 and come to rest in the upper part of storage bin SB, the pins of set C occupying the bottom portion of the storage bin. Since it is desirable that a full set of ten pins be delivered to storage bin SB, a pin counter 396 is provided. This counter preferably is mounted on the top portion of said bin SB and adjacent admission gate 364.

Pin center 396 can be of the same type and construction as counter 398 previously described. Counter 396 consists of a ten tooth ratchet wheel 620 loosely mounted on a stud 622 on which is also pivoted a counter arm 624 which extends into the path of pins moving into storage bin SB. Arm 624 is provided with an extension lever 626 carrying a spring mounted pawl 628 engaging with the teeth of ratchet wheel 620. Suitably attached to ratchet wheel 620 is a bridge plate 630 which normally connects and closes a pair of contacts 632 provided in the current supply line for cam control motor 522. Therefore, as soon as the first pin passing counter 396 and entering the storage bin depresses counter arm 624, bridge plate 630 advances with the ratchet wheel 620 and causes a break of contacts 632 which, of course, interrupts the flow of current to cam control motor 522 and consequently stops it. Since cam shaft 520 and all cams thereon are also stopped, switch arm 616 at this time, keeps contacts 618 closed, solenoid 388 remains energized and holds admission gate 384 open until the tenth pin has passed and the repeated actuation of counter arm 624 has brought bridge plate 630 again into position to engage both contacts 632. When this takes place, motor 522 is restarted to rotate cam shaft 520 which causes cam follower 614 on switch arm 616 to drop off high spot 612 of cam 516, resulting in a deenergization of solenoid 398 and a closing of gate 384 with assistance of tension spring 385. Counter 396 is also provided with a suitable tension spring 634 attached to lever 626 for the purpose of biasing lever 626 against a suitable backstop 635 after each action upon counter arm 624. A second spring mounted pawl 636 engaging with ratchet 620, prevents backlash during the counting operations.

Shortly after the pins of set B have been delivered to storage bin SB, and motor 522 and cam shaft 520 have resumed their rotation, a high and low spot 638 and 630 respectively on alley sweep control cam 506, effect the customary back and forth stroke of alley sweep S, causing the latter to sweep the pins of set A from the alley into pit P. At the same time, due to the action of a

high spot 642 on cam 510 upon cam follower 548 and switch 550, table T is caused to move upward to pin receiving position in front of triangularizing pin rack R which at this moment supports the pins of set D. During this dwell period of table T, adjacent rack R, the pin gripper mechanism is actuated through the engagement of high spot 644 of cam 508 with cam follower 554 of switch 556 which causes in grippers 124 in table T to securely grip the necks of the pins of set D projecting outwardly from pin rack R. As soon as cam follower 554 of switch 556 drops from high spot 644 onto a neutral portion of cam 508, the pin gripper mechanism is arrested, after which cam follower 548 of switch 550 drops into low spot 646 of table control cam 508. This results in the downward movement of table T which is arrested when the latter reaches its position II above the alley and cam follower 584 of switch 550 rides from low spot 646 onto a neutral portion of table control cam 510, the table carrying and holding the entire set of pin D above the alley. When table T comes to rest, high spot 648 of discharge or exit gate control cam 518 engages with the cam follower 566 of switch arm 568. This causes a closing of contacts 570 resulting in the energization of solenoid 394, which in turn opens the exit gate 390 at the bottom portion of pin storage bin SB.

The opening of gate 390 allows the pins of set C in the lower portion of storage bin SB to be delivered one by one from said storage bin onto the moving pin conveyor CO which carries them upwardly to pin rack R for delivery into the triangularly arranged pockets therein. The movement of pins of set C, out of storage bin SB, actuates pin counter 398 in the same manner as described heretofore in the previous operation, i.e. the first pin contacting counter arm 582 effects the stopping of cam control motor 522 and cam shaft 520, while the tenth pin causes motor to start again, shortly after which, cam follower 566 of switch arm 568 drops off high spot 648 which causes the opening of contacts 570 and a de-energization of solenoid 394 resulting in a closing of gate 390.

Shortly after exit gate 390 is closed, cam follower 548 of switch 550 drops into a low spot 650 of table control cam 510 effecting a downward movement of table T and a placing of pin set D on the alley. Upon reaching its lowermost position I, table T is arrested when cam follower 548 of switch 550 rides from low spot 650 onto a neutral portion of cam 510, causing a dwelling of table T in position I. During this dwell period, cam follower 554 of switch 556 drops into low spot 652 of pin gripper control cam 508, causing the actuation of pin grippers 124 in table T to open and release the pins of set D, after which the pin grippers remain open as cam follower 554 of switch 556 rides from the low spot 652 onto the neutral portion of cam 508.

As soon as the pins of set D are released in spotted standing positions on the alley, cam follower 548 of switch 550 engages with high spot 654 on table control cam 510, causing table T to move upward to its dwell position II above the alley where it is arrested as cam follower 548 of switch 550 drops from high spot 654 onto a neutral portion of cam 510. Also during this period, the backstop 192 is raised again as cam follower 606 of switch 608 engages with high spot 656 on backstop lift control cam 610 thereby starting cushion lift motor 220. The latter is stopped again as backstop 192 reaches its uppermost position and follower 606 of switch 608 drops from high spot 656 onto a neutral portion of cam 512. As soon as backstop 192 is raised, pit sweep PS receives a forward and backward motion due to the operation of reversible sweep motor 260 through high and low spots 658 and 660, respectively.

The operation of pit sweep PS cases the pins of set A to be swept from pit P into chamber F and onto the moving pin conveyor CO. As soon as the motion of pit sweep PS stops, a high spot 662 on gate control cam 516 engages with cam follower 614 of switch arm 616 which causes a closing of contacts 618 and an energiza-

tion of olenoid 388, resulting in the opening of admission gate 384 in storage bin SB. The pins of set A, which are being conveyed upwardly by pin conveyor CO through U-shaped channel U are delivered by flights 42 one by one through open gate 384 into pin storage bin SB, and on top of the pins of set B. Counter 396 is actuated in the same manner as described heretofore, the first pin stopping control motor 522, while the tenth pin causes the restarting of it and all other mechanisms indirectly controlled by said motor. Shortly after restarting motor 522, cam follower 614 of switch arm 616 drops from high spot 662 onto a neutral portion of cam 516, causing a breaking of contacts 618 and de-energization of solenoid 338, which in turn, with the assistance of spring 385, results in a closing of admission gate 384. As the pin changing cycle is now completed, the high spot 530 of motor control cam 502 contacts cam follower 526 of switch arm 528 resulting in the breaking of contacts 532 and a stopping of cam control motor 522. Before high spot 530 reaches cam follower 526, however, arm 536 also re-contacted switch 432 and closed the same. The machine is now ready again, either for normal or pin changing operation, as desired.

It can be desired to stop the pin changing mechanism after a single set of pins has been changed in order to subject sets of pins progressively in use, a control, such as shown in Figure 19, can be used. In Figure 19, cam 503 takes the place of cam 502 of Figure 18. A two arm switch closer 535 is used instead of single arm switch closer 536. When push button 525 is closed, motor 522 is started and shaft 520 begins to turn. All of the cams shown in Figure 18 operate as formerly, except that shaft 520 is stopped after 180° rotation, when either high portion 531 disengages from switch arm 528, or after one set of pins in storage bin SB has taken the place of one set of pins in the machine or in use.

The invention above described may be varied in construction within the scope of the claims because the particular embodiments, selected to illustrate the invention, is but one of several possible concrete forms of the same. The invention is not, therefore, to be restricted to the precise details of the structure shown and described.

What I claim is:

1. In a bowling pin spotting machine for use with a bowling alley, a bowling pin triangularizing magazine, means mounting said magazine above said alley in a plane substantially perpendicular to the plane of the playing surface of said bowling alley, a plurality of triangularly arranged bowling pin supporting units located in said magazine, each of said units including bowling pin supporting members for holding a bowling pin in said units in substantially horizontal position, conveying mechanism for delivering a succession of bowling pins to said magazine, and means cooperating with each of said units for effecting the selective delivery of a bowling pin to a selected unit, whereby said pins are arranged in substantially triangular arrangement for removal and placement on said alley.

2. In a bowling pin spotting machine for use with a bowling alley, a bowling pin triangularizing magazine, means mounting said magazine in a plane substantially perpendicular to the plane of the playing surface of said bowling alley, a plurality of triangularly arranged bowling pin supporting units located in said magazine, each of said units including bowling pin supporting members for holding a bowling pin in said units in substantially horizontal position, conveying mechanism for delivering a succession of bowling pins to said magazine, mechanism for orienting improperly positioned bowling pins for delivery in predetermined arrangement to said magazine, and means cooperating with each of said units for effecting the selective delivery of a bowling pin to a selected unit.

3. In a bowling pin spotting machine, a bowling pin magazine, a plurality of substantially triangularly ar-

ranged bowling pin holding stations in said magazine, a plurality of fixed bowling pin supports in selected stations, a plurality of movable bowling pin supports at others of said stations, a conveyor for conveying bowling pins to said magazine, means for guiding said bowling pins to said stations, and trips connected to selected movable supports for moving said supports to pin supporting positions in the path of travel of bowling pins in said magazine in response to the movement of said pins to said fixed supports and to movable supports which have been located in pin supporting positions by the movement of said pins.

4. In a bowling pin spotting machine, a bowling pin magazine, four spaced elongated pin guides in said magazine, a fixed support in one of said guides, a fixed pin support at the bottom of three guides, and a plurality of movable supports operatively associated with said last named three guides, said movable supports normally being located in inoperative positions, means operated in response to a bowling pin arriving upon a fixed support for moving a movable pin support into operative pin supporting position, and means operative in response to bowling pins arriving upon a movable support in traveling along two of said last-named three guides for moving another of said movable supports to operative pin supporting position, and means operative when all of said supports in said three guides are filled for delivering a pin to said fixed support in said first-named guide.

5. In a bowling pin spotting machine, a pin magazine, a plurality of elongated pin guides in said magazine, a fixed bowling pin support at the bottom of each guide, movable pin supports associated with a plurality of said guides, means normally maintaining said movable supports in inoperative position until a bowling pin is located in said fixed supports, trips actuated by a majority of said pins in said fixed supports for locating an adjacent movable support in pin supporting position, and pin actuated trips associated with said other of said movable supports for moving said last-named movable supports into operative supporting position in said guides when said first-named of said movable supports is supporting a bowling pin, in response to the movement of pins along paths by which pins are supplied to said fixed supports.

45 6. In a bowling pin spotting machine, a pin magazine, four elongated pin guides in said magazine, a fixed bowling pin support at the bottom of each guide, movable pin supports associated with a plurality of said guides, means normally maintaining said movable supports in inoperative position until a bowling pin is located in said fixed supports, trips in said guides actuated by a majority of said pins in said fixed supports for locating the movable support adjacent said fixed support in pin supporting position, other pin actuated trips in said guides associated with the other of said movable supports remote from said fixed supports for moving said remote movable supports into operative supporting position when said adjacent movable support is supporting a bowling pin, and a trap door located adjacent the entrance to three 50 of said guides constructed and arranged to be closed by the last pin entering each of said guides to control the proper delivery of bowling pins to said magazine.

7. In a bowling pin spotting machine, a bowling pin magazine, four spaced elongated pin guides in said magazine, a fixed support in one of said guides, a fixed support at the end of each of said other three guides, a plurality of movable supports mounted equidistantly along said last named three guides, means normally positioning said movable supports in inoperative positions, means operated by bowling pins engaging fixed supports in said last named three guides for moving the adjacent movable pin supports into operative pin supporting position, means operated in response to subsequent successive bowling pins moving through said last-named three guides and arriving upon a movable support for moving another nor-

mally inoperatively positioned movable support into operative pin supporting position, and means operative when all of said supports in said three last-named guides are in pin supporting position for delivering a pin to said fixed support in said first-named guide.

8. In a bowling pin spotting machine for use with a bowling alley, a pin magazine, means mounting said magazine in a fixed plane substantially perpendicular to the plane of said alley, a plurality of substantially triangularly arranged pin supporting units in said magazine, supports in each of said units for holding a bowling pin with its longitudinal axis in a substantially horizontal plane, a conveyor having a plurality of individual bowling pin conveying flights for delivering pins toward said units, means for selectively removing said pins from said flights into said units, pin guiding and positioning devices in said magazine for guiding pins delivered by said flights to said supports, a bowling pin spotter, means for positioning said spotter in a plane substantially parallel with the plane of said magazine, a plurality of pin grippers in said spotter, means for operating said grippers to grip and hold said triangularized pins in said magazine for removal therefrom by said spotter for placement on said alley, and means for moving said spotter to remove pins from said pin magazine and place them on said alley.

9. A bowling pin spotting machine for use on a bowling alley having a pit at one end thereof, means for removing bowling pins from said pit including a conveyor having a plurality of bowling pin lifting and conveying flights, a substantially vertically positioned stationary pin triangularizing magazine mounted above said pit, means for operating said conveyor to move bowling pins engaged by said flights one by one toward said magazine, a plurality of substantially triangularly arranged pin holders in said magazine, means for selectively removing said pins from said conveyor into said pin holders, supports in each of said holders for holding a bowling pin in substantially horizontal position with a portion thereof projecting outwardly from said magazine, a bowling pin setter, a plurality of substantially triangularly arranged gripper units carried by said setter, mechanism for moving and turning said setter to locate said grippers of said units in a plane substantially parallel with the plane of said magazine and in position to grip said projecting portions of said triangularized pins in said magazine, and means for operating said grippers to grip said portions of said bowling pins, and mechanism for moving said setter with triangularized bowling pins held by said gripper units away from said stationary magazine and turning said setter into pin spotting position substantially parallel with said alley.

10. A bowling pin spotting machine for use on a bowling alley having a pit at one end thereof, means for removing fallen pins from said pit including a conveyor having a plurality of bowling pin lifting and conveying flights, a substantially vertically positioned stationary pin triangularizing magazine mounted above said pit, means for operating said conveyor to move bowling pins engaged by said flights one by one toward said magazine, a plurality of substantially triangularly arranged pin holders in said magazine, means for selectively removing said pins from said conveyor into said pin holders, supports in each of said holders for holding a bowling pin in substantially horizontal position with the handle end thereof projecting outwardly in spaced substantially parallel planes from said magazine, a bowling pin setter, a plurality of substantially triangularly arranged gripper units carried by said setter, mechanism for moving and turning said setter to locate said grippers in a plane substantially parallel with the plane of said magazine and in position to engage the handle ends of said triangularized pins in said magazine, and means for operating said grippers to grip said handle ends of said bowling pin, and mechanism including means for moving and turning said

setter with said triangularized bowling pins held by said gripper units away from said stationary magazine and into pin spotting position substantially parallel with said alley.

5 11. A bowling pin spotting machine, mechanism for removing bowling pins from the pit of a bowling alley, said mechanism including a conveyor, a substantially vertically positioned stationary bowling pin magazine, supports mounting said magazine against movement, pin supporting units located in fixed substantially triangular arrangement in said magazine, said units having supporting members constructed and arranged to support bowling pins with the longitudinal axes thereof in substantially horizontal positions, means for operating said conveyor to move single pins in succession toward said units, means for selectively removing said pins from said conveyor into said units, a pin spotter, mechanism for moving and turning said pin spotter into a plane substantially parallel with the plane of said magazine, means in said spotter for gripping and holding pins in said magazine, means for moving said spotter away from said magazine for removing a set of horizontal triangularly arranged pins from said stationary magazine and for turning said spotter into pin spotting position substantially parallel with said alley.

10 12. A bowling pin spotting machine for use with a bowling alley having a pit adjacent the bowling pin supporting bed thereof, said pit having a pin supporting portion, mechanism for removing bowling pins from said pit, said mechanism including a bowling pin conveyor having a plurality of pin lifting and conveying flights, said conveyor having a closed path of travel with a substantially horizontal path of travel extending transversely across said pit, means for positioning said flights in substantially horizontal pin receiving floor forming arrangement to engage bowling pins received into said pit from said alley and move said pins across said pit to one side thereof to a substantially vertically upward path of travel of said conveyor, means for moving bowling pins from said pin supporting portion of said pit onto said substantially horizontally positioned flights, a pin magazine, means mounting said magazine above said pit and proximate one path of travel of said conveyor to receive pins delivered thereto by said flights of said conveyor to receive pins delivered thereto by said flights of said conveyor with their handle ends all extending in the same direction, triangularly positioned pin supporting units in said magazine for receiving and holding pins delivered thereto by said flights in substantially horizontal triangular formation, mechanism adjacent said vertically upward path of travel of flights on said conveyor for orienting improperly positioned bowling pins carried by said flights, and means for re-directing an oriented bowling pin downwardly onto an oncoming flight of said conveyor for movement in properly aligned arrangement to one of said units in said magazine.

15 13. A bowling pin spotting machine for use with a bowling alley having a pit adjacent the pin supporting end thereof, a pin magazine, means mounting said magazine above said pit, a plurality of bowling pin receiving positions in said magazine, a plurality of pin holding units in said magazine operatively associated with said pin receiving positions, each of said units being constructed and arranged to support a single bowling pin in substantially horizontal position with the handle ends thereof all extending in the same direction, mechanism for removing bowling pins from said pit, said mechanism including an endless conveyor encircling said magazine, flights carried by said conveyor for receiving substantially horizontally arranged bowling pins removed from said pit and carrying said substantially horizontal pins one by one for successive delivery, with the handle ends thereof all extending in the same direction, to said magazine, said flights being constructed and arranged to release

pins carried thereby at said pin receiving positions, means for effecting the transfer of pins from said pin receiving positions to said pin holding units, means for effecting the removal of improperly positioned bowling pins from the range of operation of one flight, and an orienting device for repositioning each pin removed into predetermined arrangement with the handle end thereof extending in the same direction as pins delivered by said flights to said magazine, and redirecting said repositioned pin into the range of action of another flight.

14. A bowling pin spotting machine for use with a bowling alley having a pit at one end thereof provided with a pin supporting portion, an endless conveyor having a closed path of travel with a substantial lower portion thereof substantially horizontal through said pit to engage pins in said pit and move them; a plurality of movably mounted flights mounted in spaced relation equidistantly along the length of said conveyor, a pusher for moving pins from said pit onto said horizontally positioned moving conveyor, a pin triangularizing magazine, having a plurality of pin depositing stations, a plurality of triangularly arranged pin receiving and supporting units mounted in said magazine and operatively associated with said stations, means mounting said magazine above said pit and in a plane substantially perpendicular to the plane of said bowling alley with said pin stations adjacent the upper portion of said conveyor, and means for operating said conveyor to cause said flights to lift single pins, one by one, and transport the same vertically along a side of said magazine, said pin flights being constructed and arranged to deliver pins at the upper portion of said conveyor to said pin stations for transfer in succession to said units of said magazine.

15. A bowling pin spotting machine for use with a bowling alley having a pit at one end thereof, means for removing fallen pins and balls from said pit, including a ball lift, and pin separating device, a pin conveyor having a substantially horizontal lap extending transversely of said pit constructed and arranged to receive bowling pins from said first-named means, a plurality of individual pin forwarding and lifting flights carried by said conveyor, a magazine mounted above said pit in a plane at right angles to the plane of said alley and having a plurality of pin receiving units, a plurality of fixed substantially triangularly positioned pin holding stations located in said magazine adapted to hold bowling pins in substantially horizontal arrangement, means for moving said conveyor to travel said flights toward said magazine, means mounting said flights on said conveyor to effect the release of pins lifted thereby at said pin receiving units, means for delivering pins from said pin receiving units to said pin holding stations, and means operative upon the delivery of a substantially horizontal bowling pin to one of said stations from one of said flights to condition another of said stations so as to be loaded from the next successive pin-forwarding flight of said conveyor.

16. In a bowling pin spotting machine for use with a bowling alley having a pit at one end thereof, a pin magazine, means mounting said magazine in a substantially vertical plane, said magazine having pin delivery openings in the top thereof, an endless pin conveyor located at one side of said pit, said conveyor having a substantially horizontal path of travel extending transversely of said pit, a substantially vertical pin lifting path of travel extending upwardly at one side of said pit, a substantially horizontal path of travel above and along said magazine, and a substantially vertical returning path of travel into said pit; said paths of movement of said conveyor encircling said magazine; a plurality of movable flights mounted equidistantly along said conveyor, means progressively moving said flights into substantially abutting pin floor forming relationship along said path of travel in said pit, to engage bowling pins received into said pit from said alley and to move said pins across said pit to one side

thereof for elevation by said conveyor to said magazine, means for spacing said flights in substantially horizontal parallel arrangement for a major part of said upward vertical path of travel to elevate said pins moved by said conveyor across said pit to said magazine, and means for positioning said flights in substantially vertical pin propelling arrangement above and along the top of said magazine to effect the delivery of a succession of single pins into said openings of said magazine.

10 17. In a machine of the type defined in claim 16, a U-shaped guide mounted in said substantially vertical pin lifting path of travel of said conveyor, means constraining said conveyor to move through said guide, means for positioning said flights substantially vertically to move 15 bowling pins through said guide, a device in said guide for removing improperly oriented pins from engagement with said flights, and means for maintaining properly oriented pins in operative lifting engagement with said flights for delivery in properly oriented position to said magazine.

18. In a bowling pin spotting machine, a bowling pin magazine, a plurality of spaced pin receiving stations in said magazine, a plurality of substantially triangularly arranged stationary pin holding units in said magazine 25 operatively associated with said pin receiving stations, means mounting said magazine in a substantially vertical plane, said pin stations being disposed adjacent the top portion of said magazine, a conveyor for delivering a succession of horizontally positioned pins to said magazine, said conveyor having a portion thereof disposed in pin delivering relationship with said pin receiving stations, means for causing pins carried by said conveyor to be delivered to said pin stations and hence to said units, and trip means associated with selected units, said trip means being operative in response to a pin entering one of said units for conditioning an adjacent empty unit to receive the next successive pin delivered from said conveyor to said magazine.

30 19. In a bowling pin spotting machine, a bowling pin magazine, means mounting said magazine in a substantially vertical plane, a plurality of spaced pin-receiving positions disposed along the top of said magazine, a plurality of substantially triangularly arranged fixed pin holding units in said magazine, each of said units having 35 supporting elements for holding a bowling pin in a substantially horizontal position in said magazine, a conveyor for delivering a succession of substantially horizontally positioned pins to said pin-receiving positions of said magazine, said conveyor having a stretch disposed in pin delivering relationship with said pin receiving positions, means for causing pins carried by said conveyor to be delivered to said pin receiving positions, means for delivering pins from said pin receiving stations to said pin holding units and trip means associated with selected units, said trip means being operative in response to a pin entering one of said units for conditioning an adjacent empty unit to receive the next successive pin delivered from said conveyor to said magazine.
